UNITED STATES PATENT OFFICE.

CROMWELL A. B. HALVORSON, JR., OF LYNN, MASSACHUSETTS, ASSIGNOR TO GENERAL ELECTRIC COMPANY, A CORPORATION OF NEW YORK.

INCANDESCENT ELECTRIC LIGHTING.

Application filed October 31, 1921. Serial No. 511,793.

To all whom it may concern:

Be it known that I, CROMWELL A. B. HALVORSON, Jr., a citizen of the United States, residing at Lynn, in the county of Essex, State of Massachusetts, have invented certain new and useful Improvements in Incandescent Electric Lighting, of which the following is a specification.

The present invention relates to incandescent electric lighting, and more especially to sockets for supporting the incandescent lamp.

When an incandescent lamp is used in conjunction with a parabolic reflector or a lens it is necessary in order to obtain the best results that the source of light be positioned very accurately relative to the focus of the reflector or lens. On account of the variation in incandescent lamps, especially as to the position of the filament relative to the axis of the base it has been heretofore recognized that each lamp required to be individually adjusted to bring its filament into proper focal relation.

The object of my invention is to provide an improved incandescent lamp socket which will permit a lamp connected therewith to be adjusted with facility by hand into any position and effectively held against displacement by vibration.

The form of my invention as shown in the accompanying drawing is particularly designed for use in projectors, flood lamps and automobile head lamps. Fig. 1 is a longitudinal sectional view of my improved socket with an incandescent lamp shown in position; Fig. 2 is a perspective view of the lamp engaging shell; Fig. 3 is a similar view of the spherical ring in which the lamp engaging shell is secured; and Fig. 4 is a similar view of a part frictionally engaging the spherical ring.

The lamp 1 shown in the drawing is of the single contact type, having but one contact at the end of its base to which one end of its filament 3 is connected while the other end is connected to the cylindrical shell 4 which is provided with two diametrically disposed holding pins 5.

The socket comprises an outer cylindrical shell 6 with a spherical seat enlargement 7 at its outer end and an insulating block 8 secured as by pins 9 in its inner end. In the hollow seat of the spherical enlargement 7

is fitted as by upsetting the seat part there-over after assembly a universally adjustable ring 10 having a spherical outer surface which is frictionally pressed against the outer end of the spherical seat in the shell 6 by an axially movable cup part 11 forced outwardly by a spiral spring 12 disposed within the cylindrical portion of the shell 6 and thrusting against the insulating block 8 at its other end. The cup part 11 has its open end 13 made spherical to provide good bearing contact with the universally adjustable ring 10 and its other end is made cylindrical to loosely fit within the cylindrical portion of the shell 6 and is provided with an inturned flange 14 to afford bearing surface for the end of the spring 12.

The universally adjustable ring 10 carries within it the inner socket shell 15 made of spring metal which is provided with the usual bayonet slots 16 for the reception of and locking engagement with the holding pins 5 of the lamp. The shell 15 is permanently attached to the ring 10 at their inner ends as by upsetting or soldering, and in order that the lamp may be held from any tendency to rock on its holding pins 5 the inner shell 15 is provided with spring gripping fingers 17 made by longitudinally slotting the shell wall opposite a bayonet slot 16 as at 18 and slightly deflecting the fingers toward the axis.

The center contact 19 is in the form of a headed bolt with nuts 20 thereon for binding the feed wire thereto. It passes freely through an axial bore in the insulating block 8 and at its headed end it is carried by an insulating washer 23 which loosely engages at its periphery with the inner wall of the cylindrical end of the cup part 11. The outer end of the center contact 19 is provided with a spherical seat 21 substantially concentric with the universally adjustable ring 10. A helical spring 22 surrounds the shank of the center contact and thrusts at its ends against the insulating block 8 and the insulating washer 23 and operating thereby to force the contact 19 into yielding engagement with the contact 2 of the lamp.

In order to prevent swivelling on its axis of the universally adjustable ring 10 within its socket during insertion and removal of a lamp, it is provided with a radial pin 24

extending outwardly in a slot 25 cut longitudinally in the wall of the spherical enlargement 7 of the outer shell.

While I have shown and described herein 5 the best embodiment of the invention known to me, I do not desire to be restricted thereto as it is apparent that changes and modifications can be made without departing from my invention.

10 What I claim as new and desire to secure by Letters Patent of the United States, is:—

1. A lamp socket, comprising an outer shell provided with an internal seat, a universally movable lamp engaging part disposed within said shell and adapted to frictionally and electrically contact with said seat, and a spring pressed part guided by the inner wall of said outer shell and exerting yielding pressure upon said lamp engaging part. 15

2. A lamp socket comprising a cylindrical outer shell provided at one end with an internal spherical seat, a spherical ring contacting with said seat and provided with

25 lamp engaging means, a longitudinally movable part guided by the inner wall of said cylindrical shell and provided with a spherical bearing surface at its outer end for engagement with said ring, and a spring for 30 yieldingly pressing said parts into frictional engagement with each other.

3. A lamp socket comprising an outer shell having one end slotted and provided with an internal spherical seat, a spherical ring seated in said outer shell and having

an external projection disposed in the slot in said outer shell, a lamp engaging shell secured within said ring, and a longitudinally movable spring pressed part bearing upon said ring and forcing it into frictional engagement with its seat in said outer shell. 40

4. A lamp socket comprising an outer shell provided at one end with an internal spherical seat and at the other end with a barrier wall, a universally movable lamp engaging part bearing upon said seat, a cupped part disposed in engagement with said lamp engaging part opposite said spherical seat, a spring interposed between said cup part and said barrier wall, a center contact provided with a spherical contact seat, and an axial shank and a second spring surrounding said center contact shank and operating to yieldingly press said contact seat into engagement with the lamp base. 45

5. A lamp socket comprising a lamp engaging shell of spring metal having a bayonet slot, and an inwardly deflected gripping finger formed therein between said slot and an adjacent longitudinal slot. 50

6. A lamp socket comprising a lamp engaging cylinder having a bayonet slot in one side thereof and an inwardly directed spring finger opposite said slot and normally operating to press the lamp base against the slotted side of the cylinder. 55

In witness whereof, I have hereunto set my hand this 28th day of October, 1921.

CROMWELL A. B. HALVORSON, Jr.
